A. OVALLE (VICUÑA).
APPARATUS FOR RAISING LIQUIDS.
APPLICATION FILED MAY 12, 1916.

1,304,701.

Patented May 27, 1919.

UNITED STATES PATENT OFFICE.

ALFREDO OVALLE (VICUÑA), OF SANTIAGO, CHILE.

APPARATUS FOR RAISING LIQUIDS.

1,304,701.

Specification of Letters Patent. Patented May 27, 1919.

Application filed May 12, 1916. Serial No. 97,191.

To all whom it may concern:

Be it known that I, ALFREDO OVALLE (VICUÑA), the name Vicuña being my mother's family name, a citizen of the Republic of Chile, and resident of Santiago, Chile, temporarily residing at the Hotel McAlpin, borough of Manhattan, city, county, and State of New York, have invented certain new and useful Improvements in Apparatus 5 for Raising Liquids, of which the following is a specification.

This invention has reference to means for raising liquids, the object being to produce an apparatus or pump in which liquid can 15 be raised to any height with the assistance of atmospheric pressure, the column of water acting as a piston, and without any power other than that necessary to produce the desired results.

20 It is well known that the atmospheric pressure acting inside a vertical tube of any diameter exhausted of air and full of water, having its upper part hermetically closed and its bottom part opening inside a well, 25 is equal to the weight of a column of water of the height of ten meters thirty three centimeters.

The atmospheric pressure can force up 30 water in a vertical tube exhausted of air, to the height already stated.

Then, as a consequence of this principle, any tube full of water under the same conditions, that is of a shorter length than 10 meters 33 centimeters, has in its interior a 35 latent atmospheric force equal in proportion to the atmospheric pressure, that has not been used according to the shorter length of this tube, and consequently the water in the closed top end of this tube is all the time 40 endeavoring to rise higher.

If this latent force of which I am speaking could profitably take out to the open air the water from the tube without losing the vacuum inside the tube, and of course without 45 dropping its column of water, an immense advantage could be obtained in raising water.

This is accomplished with my invention 50 which will be fully described hereinafter and the features of novelty of which will be pointed out in the appended claim.

In order that the invention may be clearly understood and easily carried into practical effect I have appended the accompanying 55 sheet of drawings in which I have illustrated

an example of my apparatus for raising liquids with the tubes placed in a vertical line.

The figure is a broken part sectional elevation showing my apparatus with two tubes 60 working on the balance principle for raising and ejecting liquids alternately from each tube to a height less than the pressure of one atmosphere.

Referring to the drawing, A is the tank 65 or any body of water. B and B¹ the tubes which raise the water, the lower ends of said tubes being submerged in the water in tank A and being each preferably provided with a valve b². A valve b³ is also provided in the 70 upper end of these tubes, D is a small tank or vessel containing water fixed to the upper ends of tubes B, B¹, the valve b³ in this end of said tubes being always submerged in the water contained in this vessel. E is a tank, 75 supported by the frame of the apparatus, into which the water from the tubes B, B¹ is discharged. F is a balanced lever, supported on its axle by the frame of the apparatus. The ends of this balanced lever 80 are forked to span the tubes B, B¹ and in each of these forked ends a pulley f¹ travels, said pulley being mounted on collars f² secured to tubes B, B¹. Fixed by collar b⁴ to tube B¹ is a connecting rod f³ eccentrically 85 secured to disk f⁴ mounted on a shaft driven by gear wheels f⁵ from pulleys f⁶. It will be seen that when motion is imparted to connecting rod f³ that tube B¹ will ascend and oscillate balanced lever F causing tube B to 90 descend and discharge its water into tank E without dropping the column of water contained therein. The two tubes being full of water and of the same weight act as a counterbalance thereby assisting in the movement 95 of said tubes. As tube B¹ ascends its lever valve b² opens and the upper valve b³ remains closed the water from tank F continuing to ascend in this tube until it reaches the limit of its stroke but as tube B¹ descends 100 its upper valve b³ opens and ejects the water without dropping the column of water contained therein. Instead of using two tubes counterbalanced I may employ one tube only, the weight of the tube and water being 105 counterbalanced by a spring. The lower ends of tubes B, B¹ are guided by the collars b⁵ fixed to the frame of the apparatus. Guides may also be provided at the upper ends of said tubes.

The following are some of the advantages obtained by the use of my invention:—

1. That it does not require a separate piston such as a pump does.
- 5 2. That no more force is required than is necessary to produce the desired results.

Having now particularly described and ascertained the nature of my said invention and in what manner the same is to be per-
10 formed I declare that what I claim is:—

An apparatus of the kind described comprising a tank containing a supply of water,

a pair of parallel tubes each having one end submerged in the water in said tank, a receptacle carried by each tube at its other end, 15 said receptacles each containing a supply of water in which said other ends of said tubes are submerged, siphon outlets carried by each receptacle, valves controlling the opposite ends of said tubes and means for reciprocating said tubes relatively to said tank.

In testimony whereof I have hereunto set my hand.

ALFREDO OVALLE VICUÑA.
